UNITED STATES PATENT OFFICE

WARREN H. DE LANCEY, OF SPRINGFIELD, MASSACHUSETTS, ASSIGNOR TO GILBERT & BARKER MANUFACTURING COMPANY, OF WEST SPRINGFIELD, MASSACHUSETTS, A CORPORATION OF MASSACHUSETTS

LIQUID DISPENSING APPARATUS

Application filed November 14, 1931. Serial No. 575,084.

This invention relates to improvements in liquid dispensing apparatus, and particularly to the class of apparatus used for dispensing gasoline and the like.

The invention relates particularly to a dispensing system of a type which is normally closed. A common example of this type of system is found in the so-called meter pump. A power-operated pump draws liquid from a storage tank through a suction pipe, having a check valve therein. The pump forces such liquid through a delivery conduit, in which a meter is interposed and which includes a flexible hose terminating with a valved nozzle. The valve in the hose nozzle is normally closed and the hose, the delivery conduit, and the suction pipe as far back as the check valve, are maintained full of liquid under pressure. It is common practice to provide in such a system a by-pass from the delivery conduit to the suction pipe and to control such by-pass by a relief valve, which opens after a predetermined pressure has been built up in the delivery conduit. This by-pass is supposed to guard against the building up of excessive pressures in the delivery conduit. It does not, however, accomplish its purpose satisfactorily in all cases and the reason is that liquid cannot escape from the suction pipe into the storage tank because of the closed check valve therein. Such check valve is a necessary element and cannot be dispensed with. As a consequence of the arrangement described, it is possible for excessive and dangerous pressures to build up in the closed dispensing system. If the apparatus is used only infrequently on a very hot day, the expansion of the liquid in the closed system will create a dangerous pressure, which cannot be relieved by the customary relief valve located and arranged as described. Instances have been found where the pressure has been built up to such an extent that the flexible hose cannot readily be bent. Such abnormal pressures, particularly in the flexible hose, create a rear hazard which needs to be overcome. It is also possible to build up a high pressure in the closed system by a liquid hammer action caused by

a sudden or snap closing of the hose nozzle valve.

The main object of the invention is the provision of means for relieving such excess pressures in a closed dispensing system of the class described and the means chosen for this purpose consists of a chamber which is connected to the suction side of the pump. Each time the pump is operated, the suction is applied to this chamber as well as to the liquid supply tank, and because of this fact the chamber is prevented from filling up with liquid to destroy its usefulness as a relief medium. When pumping ceases, there is always room in the chamber for liquid to enter and thereby relieve the pressure in the system.

Other objects will appear as the detailed description proceeds and will be pointed out in the appended claims.

The invention will be disclosed with reference to the accompanying drawing in which:

Fig. 1 is an elevational view, partly in section, of a liquid dispensing apparatus embodying the invention;

Fig. 2 is a sectional view of the expansion chamber;

Fig. 3 is a sectional view taken on the line 3-3 of Fig. 1, showing the relief-valve controlled by-pass around the pump; and

Fig. 4 is a fragmentary sectional view of the hose nozzle, showing its valve.

Referring to the drawing;—the gasoline storage tank, usually located underground, is shown in part at 5 (Fig. 1). Leading from this tank is the usual suction pipe 6, which extends to the inlet side of a suitable pump, such as the rotary pump 7. Interposed somewhere in the suction pipe is a check valve 8. Sometimes the check valve is located at the extreme lower end of the suction pipe, in which case it is called a foot valve. For the present purposes, the only essential is that there be a check valve somewhere in the suction pipe and the particular location of the valve is not of essential importance.

The dispensing apparatus shown is illustrative of a common type of meter pump.

It includes, in addition to the pump 7, a delivery conduit 15 which usually includes, as a part thereof, a flexible hose 16, terminating with a valved hose nozzle 17. Interposed 5 in conduit 15 is a suitable meter 18, the indications of which are manifested by an indicator hand 19 read with reference to a dial 20. The nozzle 17 has a valve 21 (Fig. 4), normally held closed by a spring 22 but capable of being manually opened by a lever 23. A support for the nozzle 17, when not in use, is shown at 24 and, adjacent thereto a lever 25 which may operate a switch (not shown) to control the electric motor 26 that 10 drives pump 7. The mechanism described is usually encased, except for the hose, support 24 and lever 25, by a casing 27, which encloses the space between a base 28 and cap 29. These parts 28 and 29 are interconnected 15 by pipe columns 30, which serve to support the motor, pump and meter as indicated.

It is common, in meter dispensing systems of the general character described, to provide a relief-valve controlled by-pass 25 around pump 7 to prevent the building-up of dangerous pressures in the system, when the pump is in operation while the nozzle valve 21 is closed. In this particular case, such provisions happen to be built into the pump 30 itself, as will appear from Fig. 3. The suction pipe 6 delivers liquid into a chamber 33 from which it passes through the wall of a filter 34. Liquid leaves through the upper end of the filter, entering a chamber 35 and 35 then passes into the inlet port 36 of the pump. The outlet port of the pump is shown at 37, connected to delivery conduit 15. A valve 38, normally held closed by a spring 39, blocks off communication between the outlet 40 and inlet ports. When sufficient pressure is built up in the outlet, say for example 15 pounds per square inch, valve 38 will open and liquid will be by-passed around the pump.

45 The feature of this invention is an expansion chamber 40, which is closed except for a single pipe connection 41 extending to the suction side of pump 7. The chamber, as shown, is formed from a short section of 50 pipe 42 of relatively large diameter and two caps 43 and 44 which are threaded on and close the ends of pipe 42 except for the connection 41 with the lower cap 44. The upper cap 43 may have a removable plug 45 to 55 allow opening of the chamber if and when required. The connection 41 is preferably of small diameter relatively to the pipes 6 and 15. As shown, it consists of a copper tube having an inside diameter of approxi- 60 mately one eighth of an inch. Tube 41 is connected by a union 46 to the lower end of a nipple 47, which is secured to cap 44 and the upper end of which extends upwardly into chamber 40 a short distance. Secured 65 as indicated, to the top of nipple 47 is a more

or less bell-shaped hood 48 which extends downwardly in spaced relation with the periphery of the nipple, terminating near but spaced slightly above cap 44. The nipple has an axial passage 49 communicating at one end with tube 41 and at the other with a cross passage 50 extending diametrically through the nipple. The hood 48 serves as a baffle to deflect liquid entering through passage 50 and avoid undue splashing. The chamber 40 is preferably located as high as possible in the pump casing with the idea of getting it as nearly as possible at the same level as the sight flow indicator 51, which is usually interposed between the pipe 15 and hose 16.

70 The operation of the device is as follows. Originally, the tube 41 and chamber 40 are filled with air but the first operation of pump 7 will exhaust some of this air and expel it with the gasoline. Since the suction of the pump is applied to tube 41 as well as suction pipe 6, a partial vacuum will be created within the tube and chamber 40. When the desired amount of liquid has been delivered, the 75 hose nozzle valve 21 is closed and then the motor 26 stopped. It is probable that the partial vacuum created in chamber 40 will not long exist, but this is not necessary to the success of the invention. If, after the pumping stops, the liquid in the closed system expands under the action of heat, liquid can enter tube 41 and chamber 40, compressing the air therein and relieving the pressure in the system. So also, when the nozzle valve 21 is 80 closed suddenly, rather than gradually, the backward surge of liquid can enter pipe 41 and chamber 40 and relieve the pressure. The sudden closing of the nozzle valve arrests the rapidly moving column of liquid and the 85 momentum of this column is expended on the nozzle valve. The valve is pushed and the flexible and somewhat elastic hose 16 is pulled out and stretched to some extent by the push 90 imparted to the closed valve and the hose nozzle. Then the hose contracts and there is a backward surge of liquid. It is to be noted that liquid can pass back through the meter 95 100 105 110 115 120 125 130 135 140 145 150 155 160 165 170 175 180 185 190 195 200 205 210 215 220 225 230 235 240 245 250 255 260 265 5 pump but these are not entirely satisfactory due to their tendency to fill up with liquid. Gasoline will absorb a certain amount of air and the amount which it will absorb varies directly with the pressure. Therefore, on the pressure side of the pump, air will be absorbed far more rapidly than on the suction side, resulting in the far more rapid filling up of the expansion chamber with liquid. 10 In the present case, the depletion of the elastic medium from the expansion chamber 40 is avoided. The gasoline in it will never be under heavy pressure and at times it will be under a pressure less than atmospheric and will tend to give up air. Then again, suction is applied each time the pump is operated, and liquid is drawn from the expansion chamber, if present there to any substantial degree. Thus, by the connection of the expansion chamber to the suction side of the pump, the filling up of such chamber with liquid is effectively guarded against.

Another important feature of the invention relates to its effect in connection with the sight flow indicator. Heretofore, much trouble has been experienced by the dropping of the liquid level in the glass cylinder of the indicator in between operations of the pump. The purchaser expects this cylinder to be full of liquid, and if it is not so, then his suspicions are aroused. Occasionally some liquid may leak past the check valve 8 when it fails to seat properly. A slow leak here in former apparatus of this class will in time cause a drop in level in the indicator. With the present arrangement, the liquid leakage would be replaced by liquid from tube 41 and chamber 40, the air in the latter expanding to force the liquid down. This also tends to hold the liquid at the top of the glass cylinder of the sight flow indicator as does also the column of liquid in tube 41 which to some extent at least balances the column of liquid in pipe 15. The pipes 41 and 15, in effect, 40 form the two legs of a U-tube and this arrangement helps materially in preventing dropping of the level in the sight flow indicator as has heretofore occurred.

The invention has been disclosed herein, in an embodiment at present preferred for illustrative purposes, but the scope of the invention is defined by the appended claims rather than by the foregoing description.

What I claim is:

55 1. In a liquid dispensing apparatus, a storage tank for liquid, pumping means for withdrawing liquid from the tank, a suction pipe connecting the pump and tank, a check valve in said pipe preventing return flow of the liquid drawn by said means, a delivery conduit, a normally closed valve controlling the outlet of said conduit, and an expansion chamber connected to the suction side of said pumping means.

60 2. In a liquid dispensing apparatus, a stor-

age tank for liquid, pumping means for withdrawing liquid from the tank, a suction pipe connecting the pump and tank, a check valve in said pipe preventing return flow of the liquid drawn by said means, a delivery conduit, a normally closed valve controlling the outlet of said conduit, an expansion chamber, and a conduit of relatively small cross sectional area as compared to said pipe and conduit for connecting said chamber to the suction side of the pumping means. 73

3. In a liquid dispensing apparatus, a storage tank for liquid, pumping means for withdrawing liquid from the tank, a suction pipe connecting the pump and tank, a check valve in said pipe preventing return flow of the liquid drawn by said means, a delivery conduit, a normally closed valve controlling the outlet of said conduit, an expansion chamber having in its lower wall a constantly open passage of very small cross sectional area as compared to said pipe and conduit, said chamber being closed except for said passage, and a conduit connecting said passage to the suction side of said pumping means. 80 85

4. In a liquid dispensing apparatus, a storage tank for liquid, pumping means for withdrawing liquid from the tank, a suction pipe connecting the pump and tank, a check valve in said pipe preventing return flow of the liquid drawn by said means, a delivery conduit, a normally closed valve controlling the outlet of said conduit, an expansion chamber having in its lower wall a constantly open passage of very small cross sectional area as compared to said pipe and conduit, said chamber being closed except for said passage, said passage opening into said chamber at a point adjacent but spaced from its lower wall, a conduit connecting said passage to the suction side of said pumping means, and a deflector in said chamber for deflecting liquid entering through said passage toward said lower wall. 95 100 105

5. In a liquid dispensing apparatus, a storage tank for liquid, pumping means for withdrawing liquid from the tank, a suction pipe connecting the pump and tank, a check valve in said pipe preventing return flow of the liquid drawn by said means, a delivery conduit extending upwardly from said means to a certain level and then downwardly, a sight flow indicator interposed in said conduit at said level, a normally closed valve controlling the outlet of said conduit, and an expansion chamber connected to the suction side of said pumping means and spaced substantially above the same and closely adjacent said level. 110 115 120

6. In a liquid dispensing apparatus, a storage tank for liquid, pumping means for withdrawing liquid from the tank, a suction pipe connecting the pump and tank, a check valve in said pipe preventing return flow of the liquid drawn by said means, a delivery conduit extending upwardly from said means to 125 130

a certain level and then downwardly, a sight flow indicator interposed in said conduit at said lever, a normally closed valve controlling the outlet of said conduit, an expansion chamber connected to the suction side of said pumping means and spaced substantially above the same and closely adjacent said level, and a conduit connecting said chamber to the suction side of said pump and forming one leg of a U-tube arrangement of which the delivery conduit constitutes the other leg, whereby the column of liquid in the expansion chamber conduit helps to balance the column of liquid in the delivery conduit and to avoid drop in level of the liquid in said indicator.

In testimony whereof I have affixed my signature.

WARREN H. DE LANCEY.
